UNITED STATES PATENT OFFICE.

ERASTUS E. WINKLEY, OF LYNN, MASSACHUSETTS, ASSIGNOR TO UNITED SHOE MANUFACTURING CORPORATION, OF PATERSON, NEW JERSEY, A CORPORATION OF NEW JERSEY.

SOLE-PRESSING MACHINE.

Application filed September 13, 1926. Serial No. 135,008.

This invention relates to sole pressing machines and is herein illustrated as embodied in a rotary sole laying machine of the type disclosed in United States Letters Patent 5 No. 557,744, granted April 7, 1896, on application of E. E. Winkley.

A rotary sole laying machine of the type referred to comprises an endless carrier in the form of a rotating spider, carrying a 10 number of jacks and corresponding sole engaging pads arranged to press shoes having cemented soles positioned thereon, or in other words to "lay the soles". The spider rotates by uniform steps so that each jack in 15 turn passes a "loading position" at which a treated shoe is removed and an untreated one inserted. The next cycle of movement of the machine puts this shoe under sole laying pressure which is maintained 20 through several cycles until the loading position is again approached, when the pressure is removed, the shoe taken out of the machine, and another substituted as before.

In machines of this type prior to the present invention, the sole laying pressure has been applied by means of the reaction between a cam roll carried by the spider and a cam on the machine frame. After the pressure has been applied, the roll passes 25 around a dwell on the cam to maintain it. The pressure is very great and a great deal of mechanical work is required to drag the roll around the cam, which has militated strongly against the practical success of this 30 type of machine.

In view of the foregoing the present invention provides a novel sole laying or pressing mechanism comprising, as herein illustrated, a plurality of shoe supports and sole 35 pressing pads and a locking mechanism which maintains the sole laying pressure once it is established without any substantial friction or mechanical drag in the machine. The only mechanical energy used to 40 effect and maintain the pressure is that required to build it up, a little more energy being utilized at the end of the cycle to permit the unlocking of the holding mechanism.

In the illustrated machine the locking 45 mechanism comprises, appurtenant to each jack, a hook which slips over a lug on a pressure creating member as a cam pulls the member slightly beyond its operative

pressure position. The cam then drops away from its follower, the cam mechanism 55 becoming entirely idle as to this jack until the loading position is again approached, when the pressure creating member is again actuated to relieve friction on the hook, which is then disengaged, and the pressure 60 mechanism allowed to relax.

These and other features of the invention comprising certain combinations and arrangements of parts will be apparent from the following description of a preferred embodiment of the invention shown in the drawings, in which

Fig. 1 is a front elevation of the machine;

Fig. 2 is a front elevation of the mechanism appurtenant to one jack;

Fig. 3 is a detail of a clutch mechanism;

Fig. 4 is a perspective view of a portion of the rotary carrier and the mechanism it carries; and

Fig. 5 is a perspective view of the rear of 75 the machine.

The illustrated sole pressing machine has a frame 10 which carries a rotary carrier or spider having four arms 14. The spider is rotated about an axis at 16 by a worm wheel 18 and a clutch mechanism 20. Lugs 22 spaced every 90° around the worm wheel disconnect the clutch at each quarter revolution of the worm wheel and spider and stop the machine. The clutch is actuated by a 80 treadle 24.

Between each pair of successive spider arms, at the front of the machine is mounted a jack 26 arranged to tip outwardly under spring pressure toward the front of the machine about an axis perpendicular to the axis 16. Each jack is normally held in erect position by a cam roll 28, which rides around a cam 30 having a single notch 32 in its upper side to permit the uppermost 85 jack to fall forward and outward in the loading position.

At the end of each arm 14 is pivoted a pad carrying arm 34 having a cam roll 36 co-operating with a cam 38 mounted on the frame 10 to lift the uppermost pad carrying arm about its pivot 40. The outer end of each arm 34 carries a bell crank 42 pivoted at 44 and having a sole pressing pad 46 pivotally mounted at 47, a point opposite the 90 shank portion of the pad, on one arm. This

pivotal mounting of the pad at this point centers the pressure exerted by the pad at the shank of the shoe. The other arm of the bell crank is pivoted at 48 to a rod 50 which passes through a heavy spring 52 nested in the pad carrying arm 34 and abutting against the pad carrying arm and an adjusting nut 54 on the rod 50. Thus the spring 52 tends to throw the bell crank 42 counter-clockwise (Fig. 2) and press the pad 46 down tightly on a shoe on the jack 26.

Each arm 14 of the spider carries a guide 56 in which slidingly reciprocates a rod 58 to which is fastened a lug 60 which is connected by a link 62 to the pivot 44 at the outer end of that pad carrying arm 34 which is mounted on the spider arm 14 next around counter-clockwise. The clutch between the rod 58 and the pressure mechanism is similar to that shown in United States Letters Patent No. 640,063, granted December 26, 1899, on my application. The rod 58 has teeth 64 and carries on its lower end, below its lower bearing in the guide 56, a movable box 66, through which it can slide. This box carries a pawl 68 pivoted to the box at 70. Pivoted to the pawl's tail at 72 is a link 74 whose other end is pivoted at 76 to the outer end of a bell crank 78 pivoted to the spider frame at 80. The inner end of the bell crank 78 carries a cam roll 82 which runs on a cam 83 having two humps 84, 86 and mounted fixedly on the frame of the machine. The humps throw the bell crank lever 78 clockwise as seen in Fig. 2.

A spring 88 connects the outer end of the pad carrying arm 34 with a lug on the box 66. The rear side of the box 66 has a backwardly projecting lug 90 arranged to cooperate with a hook or latch 92 pivoted at 94 on the guide 56 appertaining to the next spider arm 14 in the clockwise direction. The hook has a tail 96 arranged to ride over a cam 98 on the frame 10 to throw the hook up away from the lug 90 as it passes the cam. A spring 100 tends to throw the hook into operative position over the lug 90. A spring 102 extends from the guide 56 to the outer end of the bell crank 78. A cam 104 is arranged on the frame 10 to hold the roll 82 positively against the cam 83 at a certain time in the cycle. The cam 104 and the spring 102 are for the same purpose.

There are four pressing mechanisms on the spider, only one of which has been described above. It will be understood that all parts not mentioned as mounted on the frame are quadruplicated around the spider.

The machine operates as follows: The machine being stopped, the upper jack is tilted out toward the operator. The pad carrying arm belonging to this jack is held high by the cam 38, its hook 92 is unhooked, the spring 88 is stretched, the box 66 is held thereby up against the lower end of the guide 56, the

roll 82 is on a low part of the cam 83, the pawl 68 is out of operative position, and the rod 58 is raised so that the lug 60 is at the top of the guide 56. The operator arranges a cemented sole on a shoe, puts it on this jack and steps on the treadle. The spider begins to revolve and the jack rises into the plane of the spider.

The roll 36 falls along the cam 38 allowing the pad carrying arm 34 to fall toward the shoe, under the pull of the spring 88, until the pad contacts with it. Meanwhile the rod 58 drops down through the guide 56, the teeth 64 passing by the pawl 68. After the pad has found and settled on the shoe the roll 82 reaches the hump 84 and begins to throw the bell crank 78 clockwise. The first movement of the bell crank throws the pawl 68 into engagement with the nearest tooth 64 and further movement of the bell crank pulls down the box 66 and the rod 58 which is now locked to it by the pawl 68. The rod 58 and link 62 pull down the arm 34 still more, and since the pad 46 can come no lower, the bell crank 42 now turns, compressing the spring 52, which causes the pad to press tightly against the sole of the shoe. As the box 66 nears its position of greatest separation from the guide 56 the hook 92 falls over the lug 90, and as the roll 82 falls off the hump 84 the hook holds the box 66 in this position and keeps the spring 52 under compression. There is now no pressure between the roll 82 and the cam 83. The machine then stops with the arm 34 in a vertical position at the right of the machine, Fig. 1.

The operator removes the shoe which has now come up to the loading position on the succeeding jack, puts on another and starts the machine again. During the next two quarter revolutions of the spider the first shoe remains under pressure and no change takes place in the conditions appurtenant to it. It is carried, under pressure, from the right side to the bottom and to the left side of the machine.

At the beginning of the fourth quarter revolution of the spider the pad carrying arm 34 is in a vertical position at the left of the machine, Fig. 1, and the roll 82 is just to the left of the hump 86. It rides up the hump, releasing the pressure on the hook 92, whose tail 96 now passes under the cam 98, which tips it away from the lug 90. The roll 82 then falls rapidly under the pull of the spring 52, which lifts the rod 58 until the spring 52 has run down. The box 66 rises to contact with the "lower" end of the guide 56, and the cam 104 and spring 102 insure that the roll 82 shall fall completely to the low part of the cam 83 and thus cause the unlatching of the pawl 68. The roll 36 then begins to ride up the cam 38, lifting the pad carrying arm 34 against the spring 88 and releasing

the shoe. At the end of this fourth cycle or quarter revolution the jack which we have been following falls forward and the shoe can be removed. Thus there are normally four shoes in the machine at once: two under pressure, one having pressure applied, and one having pressure relieved.

It will be understood that the compression of the spring 52 will be always due to the same amount of movement of the rod 58, except for a possible fraction of the length of a tooth 64 so that all shoes are treated with substantially the same total pressure irrespective of individual variations in the heights of their lasts. In effect, the machine "measures" the work and then gives it a standard pressure.

By virtue of the hook 92 and its associated mechanism the shoe is held under maximum pressure for more than two cycles without the consumption of any mechanical energy. The cam roll 82 is "working" only while it goes over the humps 84, 86, that is, during a small fraction, only, of a total revolution of the spider.

In case there were no shoe on the jack, the rod 58 would overthrow downward and when the roll 82 went over the hump 84 the extra movement of the rod 58 would smash the mechanism at 44 against the upper end of the guide 56. To prevent this, the illustrated machine is provided with a safety device comprising a pin 106 mounted on the lug 60 and arranged to strike the top of the box 66. In a case such as just described the pin 106 pushes down the box 66 as the rod 58 overthrows, and lifts the roll 82 away from the low part of the cam 83. Then when the hump 84 comes along the rod 58 cannot be moved enough more to cause breakage.

Having described my invention, what I claim as new and desire to secure by Letters Patent of the United States is:

1. In a sole laying machine, a rotary carrier having an opposed jack and pressing pad, power-operated pressure mechanism to cause relative approach of the jack and pad as the carrier rotates to press a shoe on the jack, said mechanism comprising a reciprocator member and cam mechanism for operating it, and a lug and a hook one of which is mounted on the carrier and the other on the reciprocator member, said lug and hook being arranged to engage as the reciprocator member reaches its operative position and the cam mechanism being constructed and arranged to become inoperative after this engagement and to become again operative at the end of the pressure cycle thereby permitting the disengagement of the hook and lug and the release of the pressure mechanism.

2. In a sole laying machine, a rotary spider carrying a plurality of jacks and opposed pressing pads, a mechanism in connection with each pad for moving the pad to press a

shoe on the corresponding jack comprising a reciprocator member, a fixed cam on the machine frame, a lever operated by the cam arranged to act on the reciprocator member as the spider rotates to establish the pressure, a lug on the reciprocator member, a hook on the spider arranged to engage the lug as the cam operated lever reaches its extreme position, the cam being arranged to release the lever after this engagement and to pick it up again toward the end of a complete revolution of the spider, and a fixed cam for subsequently disengaging the hook, the first-named cam being constructed and arranged then to release the pressure on the shoe.

3. In a sole laying machine, a rotary spider carrying a plurality of jacks and opposed pressing pads, a mechanism in connection with each pad for moving the pad to press a shoe on the corresponding jack comprising a reciprocator member having teeth, a spring for operating said member to move the pad into contact with the shoe, a fixed cam on the machine frame, a lever operated by the cam, a pawl operated by the lever and arranged to engage one of the teeth in the reciprocator member after the pad has been located on the shoe and then to act on the reciprocator member to apply the operative pressure to the shoe, a lug on the reciprocator member, a hook on the spider arranged to engage the lug as the cam operated lever reaches its extreme position, the cam being arranged to release the lever after this engagement and to pick it up again toward the end of a complete revolution of the spider, and a fixed cam for subsequently disengaging the hook, the first-named cam being constructed and arranged then to release the pressure on the shoe.

4. In a sole laying machine, a carrier having a jack and an opposed sole pressing pad and arranged to carry the jack and pad past a loading station, a cam having a surface thereon constructed and arranged to establish sole laying pressure on a shoe on the jack in response to relative movement between the carrier and the cam, the said cam surface being limited substantially to the extent required to establish the said pressure, and a latch for maintaining the pressure, when established, independently of the cam.

5. In a sole laying machine, a pad carrier movable to carry a pressure pad toward the bottom of a shoe, a bell crank pivoted thereto and having a pressure pad mounted on one arm, and a spring mounted in the carrier and connected to the other arm to cause the pad to exert pressure on a shoe in contact with the pad.

6. In a sole laying machine, a jack, a pivoted arm movable to carry a sole pressing pad against a shoe on the jack, a sole pressing pad pivotally mounted on the arm for movement about an axis extending laterally of the shoe

in a location opposite the shank portion of the pad, and means for relatively moving the pad and jack to impart sole laying pressure to the shoe.

5. 7. In a machine for applying pressure to the bottoms of shoes, a rotary carrier having thereon a jack and a pressing member, said jack being constructed to position a last and shoe for the application of pressure to the 10 bottom of the shoe by said pressing member, mechanism for effecting relative movement of said jack and pressing member to apply pressure to the shoe in response to rotation of said carrier, and a latch constructed and 15 arranged to hold said mechanism positively in position to maintain the pressure applied thereby to the shoe independently of further rotation of the carrier.

8. In a machine for applying pressure to 20 the bottoms of shoes, a rotary carrier having thereon a jack and a pressing member, said jack being constructed to position a last and shoe for the application of pressure to the bottom of the shoe by said pressing member, a 25 cam for effecting relative movement of said

jack and pressing member to apply pressure to the shoe in response to rotation of said carrier, said cam being so constructed as to become inoperative in further rotation of the carrier after the pressure has been applied, 30 and a latch arranged to become operative automatically to hold said mechanism positively in position to maintain the pressure applied thereby to the shoe when the cam is inoperative.

9. In a machine of the class described, the combination with a shoe support, of a carrier mounted for movement heightwise of a shoe on said support, a bell-crank on said carrier, a member connected to one arm of 40 said bell-crank for applying pressure to the bottom of the shoe in response to movement of the carrier, and a spring arranged to control the other arm of the bell-crank and to yield in response to pressure of said member 45 on the shoe.

In testimony whereof I have signed my name to this specification.

ERASTUS E. WINKLEY.
